UNITED STATES PATENT OFFICE.

WILLIAM DANNER, OF NEW ORLEANS, LOUISIANA, ASSIGNOR OF ONE-HALF TO JAMES D. LACEY, OF CHICAGO, ILLINOIS.

APPARATUS FOR DISTILLING WOOD.

No. 883,091.

Specification of Letters Patent. Patented March 24, 1908.

Application filed July 9, 1907. Serial No. 382,956.

To all whom it may concern:

Be it known that I, WILLIAM DANNER, a citizen of the United States, residing at New Orleans, in the parish of Orleans and State of Louisiana, have invented new and useful Improvements in Apparatus for Distilling Wood, of which the following is a specification.

This invention relates to an apparatus for 10 treating wood by the process of destructive distillation for the production of creosote, turpentine, tar, commercial charcoal, etc.

One object of the invention is to provide a 15 novel construction of apparatus by which the process of distilling the wood may be carried out by the use in a more efficient manner of both moist (ordinary "live") steam and dry or superheated steam, whereby the elimination of the volatile constituents of the 20 wood may be effected in a cleanly, rapid and economical manner, without liability of overheating and separating the volatile elements into their component gases and thereby reducing the amount and deteriorating the 25 quality of the products.

A further object of the invention is to provide a novel construction of apparatus in 30 which a common oven or heating chamber may be used for a plurality of portable retorts of an improved type, whereby, after the process of distilling the wood in one retort is completed, said retort may be removed from the chamber and another retort inserted therein and the operation repeated, and so on, 35 thus obviating the loss of time and labor occasioned in the use of ordinary stationary retorts by the necessity of shutting down the furnace to allow the retort to cool.

Still another object of the invention is to 40 provide an improved apparatus by which the heating medium may be supplied and controlled to carbonize and convert the wood residue into commercial charcoal, and also to provide a means by which the withdrawn retort may be quickly and conveniently cooled.

With these and other objects in view, the 45 invention consists of the features of construction, combination and arrangement of parts hereinafter fully described and claimed, reference being had to the accompanying drawings, in which:

Figure 1 is a vertical longitudinal section of a wood distilling apparatus embodying my invention, showing the parts arranged for 50 use. Fig. 2 is a rear end elevation of the

same. Fig. 3 is a vertical transverse section through the apparatus. Fig. 4 is a front end elevation of the retort. Fig. 5 is a detail view showing the construction of the closure for the vapor outlet of the retort.

In the practical embodiment of my invention, I provide an oven or series of ovens in connection with one or more portable retorts for each oven, together with means for supplying live and superheated steam to heat the oven and retort therein, the steam supplying connections being, in the use of a plurality of ovens, supplied from a common steam boiler or generator, the furnace of which may be adapted to use as fuel the uncondensable gases or vapors driven from the wood and confined in the retort, thereby enabling the process to be carried out in a rapid, cleanly and economical manner.

In the drawings, 1 designates an oven or heating chamber, which is preferably of the construction disclosed; that is, comprises a corrugated sheet metal body 2 open at its forward end and closed at its rear end by a head 3, said body being inclosed by a non-conducting jacket to diminish or prevent the radiation of heat, which jacket, in the form shown, consists of inner and outer layers 4 and 5 of non-conducting material, and a covering 6 of canvas or the like properly secured in position.

A detachable door 7 is provided to close the open front end of the oven, and is constructed to form a pocket for the reception of a body of non-conducting material 8 to prevent the loss of heat by radiation therethrough. The door is formed at intervals around its marginal edge with slots or notches 9 opening outwardly therethrough and adapted to receive swivel or swing bolts 10 pivotally mounted upon a holding-ring 11 surrounding the rear end of the oven body, said bolts being equipped with clamping nuts 12 by which the cover may be securely fastened in position. A packing ring or gasket 13 is seated in a recess in the ring 11 and adapted to bear snugly against the door or cover to hermetically seal the joint and prevent the escape of the confined heat and vapors.

A pipe 14 leads from the bottom of the closed end of the oven and serves as an outlet for the tar and is provided with a controlling valve 15. This outlet connects with a conducting pipe 16 which may be connected by

similar valved outlets to a series or battery of ovens and leads in practice to a suitable tar receiver.

Arranged transversely at the rear of the oven and in close proximity to the head 3 are steam supply pipes 17 and 18 which connect in practice with the boiler or steam generator. The pipe 17 is for the supply of superheated steam and is provided with a series of 10 preferably three pendent branches 19, 20 and 21, provided with controlling valves 22. Each branch 19 and 20 connects at its lower end with a plurality of discharge pipes 23 connected by suitable couplings therewith 15 and extending therefrom through the head 3 and longitudinally along the bottom of the oven. The pipes 23 connected with each of the respective branch pipes 19 and 20 extend longitudinally within the oven on opposite 20 sides of the longitudinal center thereof and are properly arranged to lie in the space between the same and the inserted retort and are perforated for the discharge of the superheated steam into the oven, whereby the latter is 25 heated.

The pipe 18 is provided for the supply of ordinary moist or live steam to the retort, and to this end is provided with a pendent branch 24 having a controlling valve 25 and 30 connecting at its lower end with the intermediate branch pipe 21 of the pipe 17, which pipe 21 is provided, as before described, with a controlling valve 22, and is connected at its lower end through suitable couplings with a plurality or series of preferably three nozzles 35 26 extending through the head 3 a short distance into the oven above the level of the pipes 23. A steam pipe 27 leads from the pipe 17 to and through the tar conducting pipe 16 so that a proper amount of steam 40 may be supplied to heat the interior of the pipe 16 to keep the tar in a liquid condition and prevent it from clogging on its passage, said pipe 27 being provided with a controlling 45 valve 28. Leading from the upper rear end of the oven is a vapor outlet 29 closed at its upper end and provided with lateral branches 30 and 31 having controlling valves 30' and 31'. The branch 30 is arranged above the 50 branch 31 and is employed for the discharge and conduction of all vapors distilled at a temperature of 375° F. and under to a suitable condenser, while the branch 31 is employed for the discharge and conduction of 55 all vapors distilled at a temperature above 375° F. to a separate condenser, thus providing for the separate condensation of the vapors from which the turpentine and creosote are formed.

60 Arranged on the interior of the oven are track rails 32 adapted to support a retort 33, provided with wheels 34 to rest and travel on said rails. The retort is of sufficiently less diameter than the oven to leave an intervening surrounding space or chamber for

the reception of the steam from the pipes 23 and the circulation of the evolved vapors before their discharge through the outlet 29. The retort is constructed of sheet-metal and is closed at its rear end and provided at the 70 lower portion of its front end with a doorway or opening for the withdrawal of the carbonized wood remaining at the completion of the distilling operation. This doorway is adapted to be closed by a hinged door 75 35 formed with slots in its edges to receive swing bolts 36 pivoted to the retort body, said bolts being equipped with securing nuts 37 to fasten the door in closed position. The mode of manipulating the sets of bolts 80 10 and 36 to fasten and release the respective doors 7 and 35 will be readily understood.

An opening 38 is provided in the top of the retort for the insertion of the wood to be distilled and for the discharge of the vapors 85 therefrom into the oven. This opening is partially formed by a channeled ring 39, the inner and outer flanges 40 and 41 of which are connected at their base to provide a channel or recess 42. A cap or cover 43 is 90 employed to close the opening after the removal of the retort from the oven and during the process of cooling the retort, and is formed with a depending flange 44 to seat within said channel or recess. It will be 95 observed that the wall 40 is relatively higher than the wall 41, which latter limits the effective depth of the channel or recess, thus providing for a liquid sealing of the joint between the door and walls of the opening, without liability of the liquid entering 100 the retort to prevent entrance of air into the retort during the operation of cooling and final stage of carbonizing the wood residue, as hereinafter described.

105 Perforated live steam supply pipes 45 extend longitudinally along the base of the retort and are designed to discharge the steam therefrom upward through the body of wood partially resting thereon. The forward ends of the pipes terminate in rear of the doorway closed by the door 35, while the rear ends thereof extend through the rear end of the retort and are flared to provide 110 bell-mouths 46 to receive and effect a coupling connection with the inner ends of the nozzles 26 when the retort is inserted as shown in Fig. 1, whereby steam from the steam supply connection will be furnished to the retort for discharge through the pipes 45. The arrangement of the parts is such that the coupling ends 46 of pipes 45 will align with the nozzles 26 and be brought automatically into connection therewith upon the insertion 115 of the retort to its proper operative position 120 within the oven. A tar outlet 47 is formed in the bottom of the retort and so arranged as to overlie the outlet 14 when the retort is in position, and this outlet may be closed when the retort is removed by a plug 48. At the 125 130

rear end of the retort a hook or other draft connection 49 Fig. 1 is provided for the attachment of a rope or cable to enable the retort to be conveniently drawn into the oven. This rope or cable will extend outwardly for operation through an opening 50 formed in the head 3, through which said rope or cable may also be withdrawn after the retort is inserted. The opening 50 is designed to be closed by a screw cap 51 during the distilling operation.

In operation, the retort is first filled with wood divided into pieces of a suitable size to be commercially available as charcoal after distillation. The door 35 is then securely fastened and the retort drawn into the oven through the open end thereof, which is closed by the door 7, it being understood that before the application of the retort the plug 48 and cover 43 are removed and that when the retort is fully inserted in position the pipes 45 will couple with the nozzles 26, while the tar outlet 47 will be disposed above the outlet 14. The apparatus thus being charged for use, the valve 15 is opened for the escape of the tar, the valve 30' opened for the discharge of the lighter turpentine vapors, and the valves 22 of the branch pipes 19 and 20 and valve 25 of branch pipe 24 opened for the respective supply of superheated steam and live steam through the pipes 23 and 45 to the interior of the oven and interior of the retort, the valve 31' in the vapor outlet branch 31 and the valve 22 in the branch 21 remaining closed. As a result, the retort will be heated to distil the wood, the tar from which will discharge through the outlet 40 and pipe 14, while the vapors will pass through the opening 38 into the oven and thence discharge through the pipe 30. When all the turpentine vapors are driven off, the valve 22 in branch pipe 21 and valve 31' in vapor outlet 31 are opened and the valves 25 and 30' closed, whereupon superheated steam will be supplied to both the oven and retort to increase the temperature and the heavier volatile vapors evolved from the wood will be discharged through the vapor outlet 31. Under this increase of temperature all the volatile constituents of the wood will be driven therefrom and the wood will be carbonized. When the carbonizing action has progressed to the desired degree, the valves 22 are closed to cut off the supply of steam to the oven and retort, which are allowed to cool for a period of say two hours, when the valves 15 and 31' are closed, the door 7 detached and the retort redrawn from the oven, after which the tar outlet 47 is closed by the plug 48 and the outlet 38 closed by the cover 43. Water from a suitable overhead pipe is then sprayed down upon the closed retort, the pipes 45 of which are also closed at their ends 46 by suitable caps or plugs, until the

retort is thoroughly cooled, during the progress of which another filled retort is run into the oven for a second distilling operation, and in this manner retort after retort is inserted and removed, thus enabling a continuous distilling action to be carried on with the attendant result of economy of operation, inasmuch as the shutting down of the apparatus for any considerable length of time is avoided. During the operation of cooling the retort the water flows into the channel 42 and effects a seal to prevent the escape of the remaining vapors and entrance of water to the interior, the vapors being extracted in any convenient manner for use as fuel. It will be observed that by extending the wall 40 above the wall 41 of the channel 42, the liquid will flow over the wall 41 after the channel is completely filled, while the greater height of the wall 40 will prevent the overflow liquid from entering the retort through the outlet 38. After the retort has been cooled, the wood, which has by the operation described been carbonized into commercial charcoal, is removed by opening the door 35 and tilting the retort to discharge the wood through the door way.

As before described, a series of ovens may be employed and a series of retorts used in connection with each other, and the uncon- densable vapors may be conducted from the parts of the apparatus in any suitable manner and utilized as fuel for the burners or furnace of the steam generator, thus securing further economy. The saving in point of time and labor effected by the construction of the apparatus for continuous use and avoidance of the necessity of shutting down for any considerable period will be appreciated, and owing to the use of live and super- heated steam as the heating agent, it will be apparent that the distilling process may be carried out in a cleanly manner and the temperature controlled more efficiently to prevent the separation of the vapors into their component gases, by which a greater quantity and higher quality of products are obtained. Incidentally, also, the conversion of the wood residue into commercial charcoal allows this usual waste material to be sold as fuel, thus further decreasing the cost of maintaining and operating the plant.

Having thus described the invention, what I claim as new and desire to secure by Letters Patent is:

1. In a distilling apparatus, the combination of a horizontal oven closed at one end and provided with a doorway at its opposite end, a door for closing said doorway, track rails extending longitudinally within the oven, a retort comprising a vessel closed at one end and provided with a doorway at its opposite end, and a door for closing the same, said retort being provided with wheels to traverse said rails, heating pipes extending longitudi-

nally within the oven, heating pipes extending longitudinally within the retort and having entrance ends projecting through the closed head thereof, steam supply nozzles 5 adapted to automatically couple with and uncouple from said entrance ends upon the insertion and removal of the retort, and a system of valve supply pipes for supplying superheated steam to the pipes within the 10 oven and either live or superheated steam to the nozzle.

2. In a distilling apparatus, the combination of a horizontal retort having track rails therein and closed at one end and provided 15 with a doorway at its opposite end, a door for closing the doorway, a retort comprising a vessel having an opening and a closure therefor at one end and provided with a vapor outlet in the top thereof, a vapor 20 charge pipe leading from the oven and provided with valved branches located at different elevations, heating pipes extending longitudinally within the oven, heating pipes within the retort having their inlet ends projecting through the closed end wall thereof, steam supply pipes upon the closed end of the oven including nozzles to telescopically engage the inlet ends of the retort pipes, main live and superheated steam supply 25 pipes, and valves controlling the passage of steam and arranged for the supply of superheated steam to the oven and either live or superheated steam at will to the retort.

3. In a distilling apparatus, an oven closed 35 at one end and open at the other end, the closed end being provided with an opening, a door for closing the open end of the oven, a removable retort having an open end provided with a door and a closed end provided with a 40 draft member for connection with a cable or the like adapted to pass through the said opening in the closed end of the oven, a closure for said opening, and means for supplying a heating medium to the oven and retort.

4. In a distilling apparatus, an oven, a retort insertible therein and withdrawable therefrom, pipes for supplying superheated

steam to the oven, nozzles for supplying live steam to the retort, steam pipes upon the retort adapted to connect with said nozzles, 50 and valves controlling the first named pipes and nozzles for supplying superheated steam to the oven and either live or superheated steam to the retort.

5. In a distilling apparatus, the combination of an oven, a retort disposed therein, said oven and retort being provided with heating pipes, main live and superheated steam supply pipes arranged exteriorly at one end of the oven, valve branches from the 60 superheated steam supply pipe to supply steam therefrom to the oven pipes, and branches from both main supply pipes for the supply at will of either live or superheated steam to the retort pipe, said branches 65 being provided with valves controlling the flow of steam from the respective main pipes.

6. In a distilling apparatus, the combination of an oven provided with steam heating pipes, a retort therein provided with steam heating pipes, main live and superheated steam supply pipes disposed exteriorly at one end of the oven, branches from the superheated steam supply pipe to the oven heating pipes, valves controlling the same, associated 70 connections from both supply pipes to the retort heating pipes, and valves for controlling said connections, whereby either live or superheated steam may be supplied at will to the retort pipes.

7. In a turpentine distilling apparatus, an oven, a retort therein, means for supplying superheated steam to the oven, means for independently supplying either live or superheated steam to the retort, and means for supplying both kinds of steam to the retort 85 in a commingled condition.

In testimony whereof, I affix my signature in presence of two witnesses.

WILLIAM DANNER.
